I. G. HUDSON

UNDERGARMENT CONSTRUCTION

Filed Dec. 2, 1926

FIG. 1.

FIG. 2.

Ida G. Hudson

INVENTOR.

BY *S. J. Miller*
ATTORNEYS.

UNITED STATES PATENT OFFICE.

IDA G. HUDSON, OF OKLAHOMA CITY, OKLAHOMA.

UNDERGARMENT CONSTRUCTION.

Application filed December 2, 1926. Serial No. 152,287.

My invention relates to undergarment construction.

The object of the invention is to provide a type of construction for women's undergarments which is new, novel and of utility, which will allow the nursing of a child without the removal of the undergarment, which will at the same time support the breasts and allow expansion, which will eliminate the danger of permanent injury to the wearer because of binding, which may be used in the manufacture of brassière, corsets, or any other undergarment for the upper portion of the body.

It is a matter of common knowledge that during the period of pregnancy, and during the period of child nursing the breasts of a woman are enlarged to greater than normal size. If the breasts are not supported in any way during this period they become elongated and unshapely. If a garment of the pattern now prevalent is used, the breasts are bound too tightly and there is great danger of permanent injury to the milk forming glands of the wearer. Also under the garments in present use it is necessary during the period of nursing the child to remove the garment for the nursing of the child. It is to eliminate these objections that the construction herein described was designed, and invented.

With the above and other objects in view as will more fully appear from the specification, claim, and drawing, my invention consists in the details of construction to be more fully described hereinafter. One construction embodying my invention is shown in the accompanying one sheet drawing, in which,

Figure 1 is a perspective view of the brassière incorporating my construction. Fig. 2 is a perspective and illustrative view of a barcolette incorporating my construction.

Like characters of reference designate like parts in all the figures.

The type of construction consists in patterning the front part of the garment with two substantially V-shaped openings 1, 2, spaced as desired to conform to the body of any sized woman as desired. V-shaped flaps 3, 4, are provided for each of said openings

and are securely fastened along the outer edge of each opening at 5, 6. The top edge of each flap is tucked and equipped with an elastic band as at 7 and 8. Between the 55 openings in the garment the material is folded in three large pleats 9, 10 and 11, to allow for expansion. The upper edge of the material between the openings is tucked and equipped with elastic also as at 12. 60 The inner edge of each opening is also equipped with elastic as at 13, 14. The flaps 3, 4, are held closed by hooks which are secured to the corners of the flaps at 15, 16. The hooks 15, 16, engage eyelets at 17, 18. 65

In wearing a garment of this construction either the flaps may be unhooked thus baring the breast for nursing. When hooked the elastic binding and the pleats and tucks in the material allow the garment to conform to 70 the body of the wearer and at the same time the garment supports the breasts of the wearer without binding and without injury in any way.

The invention upon which this application 75 is based is broader than the specific illustration shown in the accompanying drawing. It is to be understood that I reserve the right to make such changes in the construction set forth as will not depart from the 80 original spirit of the invention, nor the scope of the subjoined claim.

I claim:

In combination, the bosom covering portion of an undergarment, as described, having two substantially V-shaped sections spaced to engage the breasts of the wearer and having their apexes extending downwardly, said V-shaped sections fitting over similar shaped apertures in the garment, being fixedly secured to the garment along their outside edges, and being detachably secured to the garment along their inside edges, both adapted to be opened, thus barring the breasts of the wearer, elastic bands, 85 tucks and gathers, along the upper edge of said V-shaped sections and along the three edges of the garment which lie between the V-shaped sections, all adapted to support the breasts of the wearer without binding. 90 95

IDA G. HUDSON.
